J. LE GAUCEAR

ELECTRIC COIL

Filed Sept. 2, 1924

UNITED STATES PATENT OFFICE.

JACQUES LE GAUCLEAR, OF CHICAGO, ILLINOIS, ASSIGNOR OF ONE-HALF TO EDWARD E. McMORRAN, OF CHICAGO, ILLINOIS.

ELECTRIC COIL.

Application filed September 2, 1924. Serial No. 735,508.

While the present device may be utilized for any purpose for which it may be adapted, it is particularly applicable for use in connection with radio apparatus. One of the principal features of this invention is the arrangement of a primary coil having predetermined taps which coacts with a secondary coil also having predetermined taps or coil windings which are arranged in accordance with the taps or windings of the primary coil and synchronously operating movable wipers or contact members which are adapted to coact with the contacts on the primary and secondary coils.

The objects of this invention are to provide an improved electrical coil for radio purposes; to provide primary and secondary coils having predetermined lengths of windings arranged in predetermined relation to each other; to provide a simple and compact device of this character which is adapted for use in receiving sets and which will be particularly efficient in operation; and to provide such additional features and details of construction as will be described more fully hereinafter.

In the accompanying drawings illustrating this invention,

Figure 1 is a side view with parts broken away to show the interior construction;

Figure 2 is a longitudinal sectional view; and

Figure 3 is a diagrammatic view illustrating the windings of the respective coils.

The theory of operation and general principles governing this apparatus will be best understood from Figure 3. Both the primary and secondary coils are of the kind commonly known as "tapped" coils and while the lengths of the different turns may be varied for different purposes or conditions, I prefer to make them in exactly the following manner. The first turn on the primary coil as indicated at B is four inches long so that there will be exactly four inches of wire in the circuit when the wiper is on contact No. 1. The length of turns is then increased four inches for each succeeding tap, for instance, the length of wire between taps 1 and 2 as indicated at c would be eight inches; between taps 2 and 3 as indicated at D would be twelve inches; between taps 3 and 4 as indicated at E would be sixteen inches; and so on for the entire coil, there being 36 taps or contacts for the primary.

The length of wire or windings in the secondary coil is three times that of the respective windings or coils in the primary. For instance, the length of wire as shown at F up to the first tap or contact would be twelve inches long; between contacts 1 and 2 as indicated at G the wire would be twenty four inches long; between contacts 2 and 3 as indicated at H the wire would be thirty six inches long; between contacts 3 and 4 as indicated at I the wire would be forty eight inches long, and so on, the secondary also having 36 taps or contacts. The wipers for the two coils are arranged so that they operate in unison whereby the same proportion is maintained between the coils at all times. The particular apparatus as shown in Figures 1 and 2 comprises a casing 6 having a flange 7 at one end which is provided with holes 8 for convenience in mounting it in a board or panel. The opposite end of the housing has a cover 9. A shaft 10 passes through the housing and is provided with a knob 11 for turning the same, such knob being preferably formed in combination with a dial 12 for indicating the position of the wipers.

A double spool 13 for supporting the coils is mounted in the housing 6 and is concentric with the shaft 10. This spool is preferably provided with grooves 14 and 15 for the respective primary and secondary coils. This spool is preferably made of insulating material such as bakelite, rubber or the like and has an outwardly projecting cylindrical flange 16 at one end thereof. A series of contacts 17 are secured in this flange in any suitable manner but preferably by being cast therein. These contacts are preferably knurled or threaded as shown at 18 for holding them in position and their inner ends are preferably flush with the inner surface of the flange 16. Their outer ends are provided with grooves 19 for convenience in securing or fastening the turns or taps of the wire forming the coil, thereto. One end of the wire forming the primary coil 20 is secured to a contact or binding post 21 which post may also serve for holding the spool in position. The first length of four inches as indicated at B in Figure 3 is then wound around the spool and the wire is then connected to the first tap or contact 17. The next winding of eight inches is then made and the wire attached to the second contact 110

and so on until the taps have been made for the entire 36 contacts.

The spool 13 has a flange 21' on the opposite end to the flange 16 which is provided with a series of contacts 22 for the secondary coil 23. One end of this coil is connected to a binding post 24 and the respective turns or connections are made the same as with the primary coil with the exception that the turns are longer as heretofore described.

Two brushes or wipers 25 and 26 are mounted on the shaft 10 to revolve therewith. These brushes are adapted to make contact with the series of contacts 17 and 22 for the primary and secondary coils respectively. While any suitable wipers may be utilized, I prefer to use a wiper having a tubular arm 27 for receiving a brush or contact member 28 which has a sliding fit therein and which is pressed outwardly against the contacts by means of a spring 29. The leads from the apparatus to the wiper arms may be made in any suitable manner but if desired a circuit wire 30 may be connected with a binding post 31 having a contact finger or brush 32 for engagement with the shaft 10 for completing the circuit to the respective wipers 25 and 26.

It will be seen that whenever the shaft is turned to cut in a number of turns or lengths of the primary, it will also cut in the same number of lengths or turns of the secondary and the relation between the primary and secondary will remain constant. While the ratio may be varied, I have found that the ratio of three to one as heretofore described is a particularly desirable and efficient one. It will of course be noted that the wires in the respective coils are insulated and are bared or stripped wherever necessary for making engagement with the contacts.

It will also be noted that various changes may be made in the details of construction and arrangement of parts without departing from the scope of this invention as set forth in the following claims in which I claim:

1. An electrical primary coil having a tap taken off at a predetermined distance from the end thereof and succeeding taps taken off at a multiple of said distance, a secondary coil having a tap taken off at a predetermined distance from the end, and succeeding taps taken off at distances which are always multiples of the corresponding section of the primary coil, and mechanically connected contacts for engagement with the taps of the respective coils.

2. The combination with a primary coil

having taps taken off at distances which increase in a predetermined ratio, of a secondary coil also having taps taken off at distances which increase in a predetermined ratio, coacting contact members for engagement with the taps of the respective coils and manually operable means for operating said contact members simultaneously.

3. The combination with a primary coil, of a series of thirty six contacts, said contacts being connected with the coil whereby the coil will be divided into sections which increase in length in a predetermined ratio, a secondary coil, thirty six contacts for said secondary coil, said contacts being connected with the coil to provide sections of a predetermined ratio, contact members adapted to engage with the contacts of the primary and secondary coils respectively and means for simultaneously actuating said contact members.

4. In a device of the character set forth, the combination of a casing, a spool mounted in said casing, a primary coil mounted on one end of the spool, contacts for said primary coil, a secondary coil mounted on the other end of the spool, contacts for said secondary coil, a rotatable member passing through the spool and wipers on said member for engagement with the contacts of the respective coils.

5. In a device of the character set forth, the combination with a spool having outwardly projecting flanges at the ends thereof, a primary coil mounted at one end of the spool, a series of contacts mounted in the adjacent flange and connected by taps with said primary coil, a secondary coil mounted at the opposite end of the spool, a series of contacts mounted in the adjacent flange and connected by taps with the secondary coil, a shaft passing through said spool and wipers on said shaft for engagement with the contacts of the respective coils for completing electric circuits.

6. In a radio apparatus, the combination of a casing, a spool mounted in said casing and having flanges in the ends thereof, a primary coil mounted at one end of the spool, taps for the primary coil secured in the adjacent flange, a secondary coil in the opposite end of the spool, contact taps for the secondary coil mounted in the adjacent flange, a shaft through said casing and spring pressed brushes mounted on said shaft and adapted to engage with said contacts for completing electric circuits.

JACQUES, LE GAUCEAR.
